UNITED STATES PATENT OFFICE

167,123

BAKING PAN

James Teague, Chicago, Ill.

Application March 5, 1952, Serial No. 18,779

Term of patent 14 years

(Cl. D44—1)

To all whom it may concern:

Be it known that I, James Teague, a citizen of the United States, residing at Chicago, county of Cook and State of Illinois, have invented a new, original, and ornamental Design for a Baking Pan, of which the following is a specification, reference being had to the accompanying drawing, forming a part thereof, in which:

Figure 1 is a top plan view of a baking pan, showing my new design;

Figures 2 and 3 are adjacent side elevational views;

Figure 4 is a partial sectional view of the pan bottom taken substantially along the line 4—4 of Figure 1; and

Figure 5 is a partial sectional view of the pan bottom taken substantially along the line 5—5 of Figure 1.

I claim:

The ornamental design for a baking pan, as shown.

JAMES TEAGUE.
